UNITED STATES PATENT OFFICE.

E. Y. ROBBINS, OF CINCINNATI, OHIO.

BABY WALKER AND JUMPER.

Specification of Letters Patent No. 16,150, dated December 2, 1856.

To all whom it may concern:

Be it known that I, E. Y. ROBBINS, of Cincinnati, in the county of Hamilton and State of Ohio, have invented a new and improved apparatus to enable a child to stand and walk and to amuse him and protect him from injury against furniture and also to give his arms and chest an invigorating and healthful exercise; and I do hereby declare that the following is such a full and exact description thereof, reference being made by the letters to the accompanying drawings, as will enable others skilled in the art with which it is most nearly connected to make and use my invention.

Four pieces of strong wood for the legs or posts K, Figures I and II of sufficient length and of about an inch more or less in diameter, (having been steamed or otherwise prepared) are bent outward at the bottom to give a breadth of base sufficient to prevent danger of overturning; ascending they gradually approach each other till nearly as high as the child's waist; whence they ascend nearly perpendicularly, to about the height of his head, from which point they are again bent inward till the four pieces meet and are firmly attached together at the top P above the child's head; or the four legs may be made of two pieces of double length crossed in the middle and each end bent downward till it assumes the shape above described. Upon the bottom of the legs are placed casters H Fig. I to enable the child to push himself about the room. A few inches above the floor is a hoop G, Fig. I attached to the legs, which is covered with velvet, plush or other soft material to prevent injury to furniture against which it may strike. This may also be wrapped with tinsel or otherwise ornamented. Upon the outside of the legs may also be fastened velvet rubber or other soft covering. At the height of the child's waist is placed another hoop B Fig. I over which is stretched canvas or other strong stuff; and over this there may be a second covering of finer texture. This covering of canvas, &c., A Fig. I is stretched entirely across this hoop except a circular opening in the middle a little larger than the child's waist, in which for him to stand, and a slit extending from this opening to the hoop behind the child's back allowing the covering to be drawn aside either way the more easily to admit the child. This circular opening is bounded by a belt

B' Figs. I and II, to which is attached a buckle C Figs. I and II, to fasten it about the child's waist; or the opening may be made sufficiently large easily to admit the child and the slit and buckle omitted. A skirt F, similar to the skirt of a child's dress is suspended from near the edge of the opening. Within this skirt and concealed by it and suspended from the belt is a seat made of canvas, drilling, or other soft material. This seat may be attached to the belt by buckles K' Fig. IV or similar fastenings by which it can be elevated or depressed at pleasure and thus be made to support more of less of the child's weight so that he shall bear as much or as little upon his legs as the parent may think proper or the child's age justify. To the upper part of the frame around and above the child's head are attached several elastic or other cords M, N, Fig. I and various ornaments and playthings are suspended therefrom as tassels, rattles, rings, bells, &c., L, O, R', &c., in reaching after and playing with which the child will be induced to pull upon the elastic cords and thus exercise his arms and chest. The lower hoop is made larger than the upper to protect the child's fingers from being crushed between the upper hoop and any article of furniture against which he may push himself. To give greater lightness the posts are dressed to a much smaller size above the upper hoop than they are below it and the whole should be made as light as is consistent with sufficient strength. Finally upon the top is fastened a knob P, or other handle by which to lift and carry the whole.

Another form of internal arrangement.— The internal arrangement of the apparatus may be varied as follows: The hoop over which is stretched the covering of canvas, &c., instead of being fixed to the posts, as in the first form B Fig. I may be made just large enough to play freely up and down, and revolve, between or inside of the posts as represented at B''. Fig. II, being suspended from the upper part of the frame by cords W, Fig. II, attached to a spring S', Fig. II, and swivel S', Fig. II, enabling the child to turn himself about in any direction without turning the frame of the apparatus itself, and the legs may be kept steady and in place by another hoop A', Fig. II, fastened to them immediately below the covered hoop B''.

This hoop A' may be wrapped in a manner similar to the bottom one G, Fig. I. In this form the covered hoop B'', Fig. II, in which the child stands, may have a rim Z, Fig. II, extending around on the upper side of it a little smaller in circumference than the hoop itself, for his hands to rest upon to prevent his fingers from being injured between the hoop and the posts. This rim 10 may be made by connecting a large wire or light wooden hoop with the main hoop, B'', Fig. II, by canvas or some fabric similar to that with which the main hoop is covered. The cords by which this hoop is suspended 15 may be kept apart by, or attached to, crossed pieces T, T, Fig. II, or some equivalent device, and instead of the elevation or depression of the seat being effected by buckles placed at its attachment to the belt the same 20 result may be produced by a single buckle Z', Fig. II, and strap R placed near the top above the child's head. In this variation the playthings and exercising cords instead of being suspended from the posts themselves, as in 25 the first form, may be suspended from a small hoop a, Fig. II, or equivalent device, attached to the swivel and revolving with it. Also in this form the exercising cords and those by which the playthings are suspended should be nonelastic. By this arrangement the child can not only turn himself around in any direction within the apparatus at the same time that he pushes himself freely about the room but he will 30 be enabled and induced to give himself a perpendicular or springing motion, not merely by the exertion of his feet and legs but, what is far more important, by the exertion of his arms in reaching after and 35 pulling at his playthings and in pulling upon the cords by which he may raise himself up. Thus the child by his very sports and amusements will be tempted into the most beneficial and healthful exercise of the 40 arms and chest. As a further inducement and assistance to this two ivory or other 45

rings R, R, Fig. II, may be suspended from above for him to pull upon.

The spring may be used without the swivel or the swivel without the spring. In 50 using the swivel without the spring the internal arrangement last described and represented in Fig. II may be varied thus. Let the springs S, be omitted, as shown in Fig. III, and let the lower end of the suspending 55 cords W instead of being fastened to the movable covered hoop B'', Z, Fig. II, be attached to a seat E, Fig. III, and this seat suspended so as to revolve within the opening of a fixed covered hoop as represented at 60 A, B, Fig. I, no seat being attached by buckles or otherwise to the belt or covering of this hoop as represented in the other forms.

If it should be found necessary an additional hoop or more than one may be attached at any degree of elevation at which it may be deemed necessary. Variations in the arrangement of playthings, ornaments, cords, size and height of frame, curvature 70 of legs, decorations, and other minor changes may be made at pleasure.

What I claim as my invention and desire to secure by Letters Patent, is—

The arrangement of the upward extension 75 of the broad-based caster-supported frame of the apparatus around and over the head of the child placed therein for the purpose of preventing his head from coming in contact with articles of furniture as he moves 80 himself over the floor, and forming a support for the jumper, (or child-sustaining canvas-covered hoop,) and also serving the purpose of suspending toys above the head of the child and within his reach to amuse 85 him and at the same time cause him to judiciously exercise his arms and chest, substantially as set forth.

E. Y. ROBBINS.
